George A. Lyon, Jr., 290 Lake Park, Birmingham, Mich.

Filed May 10, 1957, Ser. No. 46,105

Term of patent 14 years

(Cl. D4—2)

FIG. 1

FIG. 2

FIG. 3FIG. 4FIGURE 1 is a plan view of a two-bowl sink, showing my new design;

FIGURE 2 is a cross-sectional view thereof taken on line II--II of FIGURE 1 looking in the direction of the arrows;

FIGURE 3 is a front elevational view; and

FIGURE 4 is an end elevational view thereof.

The dominant features of my design reside in the portions shown in full lines.

I claim:

The ornamental design for a two-bowl sink or similar article, substantially as shown and described.
